COUCH BED

Joseph Martin, Laurelton, N. Y., assignor to
 United States Cabinet Bed Co., Brooklyn, N. Y.,
 a corporation of New York

Application April 4, 1935, Serial No. 14,573

9 Claims. (Cl. 5—18)

This invention relates to couch beds in general and more especially to seat forming furniture that can be converted into a couch or a bed such as chairs or love seats mainly used as seats which can be converted into bed formation.

Among the objects of the present invention, it is aimed to provide an improved couch bed, such as a love seat having a main bed section singly affording two adjacent seating spaces and 10 having associated therewith two extension bed sections which may be extended relative to said main bed section to form a full length double bed formation.

It is still another object of the present invention to provide an upholstered combination including a couch bed having a main bed section in length affording two adjacent seating spaces and two extension bed sections operatively associated with said main bed section and of substantially the same length which may be extended relative to said main bed section to form 20 a full length double bed formation, the upholstered combination consisting of two mattress sections extending the full length of the main bed section and adapted to be placed upon one another in love seat formation, and a pair of upright pillows, the combined length of which corresponds to the length of said main bed section which form the back for said main bed section in love seat formation and which combine with said two mattress sections to cover said several bed sections in extended or double bed formation.

It is still another object of the present invention to provide an improved frame for the intermediate section of a three section double bed formation as a result of which the longitudinal sides of the spring fabric portion may be freely flexible and yet the end portions effectively supported relative to one another, effectively braced in parallel arrangement, and the spring fabric portion maintained taut without encumbering the longitudinal sides of the intermediate bed section beneath the spring fabric portion with rigid side bars or the like.

It is still another object of the present invention to provide an improved combined seat and bed having a main section singly affording a seat and having associated therewith two extension sections which may be extended relative to said main section to form a full length bed.

These and other features, capabilities and advantages of the invention will appear from one specific embodiment thereof illustrated in the 55 accompanying drawings in which

Figure 1 is a front elevation of the combination couch bed in love seat formation;

Fig. 2 is a section on the line 2—2 of Fig. 1 on an enlarged scale;

Fig. 3 is a fragmental section on the line 3—3 of Fig. 2 on a smaller scale than that shown in Fig. 2;

Fig. 4 is a fragmental side elevation of the bed couch in double bed formation on a smaller scale than that shown in Fig. 3;

Fig. 5 is a plan view of the bed couch in double bed formation on the same scale as that shown in Fig. 4;

Fig. 6 is a fragmental front elevation partly in section on the same scale as that shown in Fig. 2 showing the relation of the several bed sections when nested in one another;

Fig. 7 is a fragmental perspective of the metal frame of the main bed section;

Fig. 8 is a fragmental perspective of the intermediate extension bed section; and

Fig. 9 is a fragmental perspective of the outer extension bed section.

The bed couch constitutes a love seat affording two adjacent seating spaces in nested or closed position and a double bed formation when extended and comprises the main bed section 1, an intermediate bed section 2 and an outer extension bed section 3. The main bed section 1 and intermediate bed section 2 are supported independently, the main bed section on the four rollerless feet 4, the lower ends of the rear metal legs, and the lower face of the horizontally extending flange of the angle iron 21, and the intermediate bed section on the four casters 5 at the four corners of the intermediate bed section while the outer or extension bed section depends in part for support on the intermediate bed section, it only having casters 6 at its outer corners while its inner corners are provided with pins 7 which ride on the inwardly extending flanges 8 of the end angle irons 9 of the intermediate bed section 2.

The four rollerless feet of the main bed section are part of an outer decorative frame composed of wood or the like and suitably covered including two side frame members 10 and 11 which form upwardly extending side arms 12 for the couch bed in love seat formation.

The main bed section is composed of two L-shaped end members 13 and 14 having the crossbar portions 15 and 16 supporting the ends of the spring fabric section 17. The rear upper ends of the crossbar portions 15 and 16 are connected to one another by the longitudinally ex-

tending angle iron 18. The lower ends of the downwardly extending portions 19 and 20 are connected to one another by the longitudinally extending angle iron portion 21 to form a U-shaped member, the upper ends of the portions 19 and 20 being connected to the front end portions of the crossbar portions 15 and 16. To reinforce the corners between the longitudinally extending bar 18 and the cross-bar portions 15 and 16, there are preferably provided the inclined metal straps 22, see Fig. 5, and to reinforce the corners between the longitudinally extending portion 21 and the downwardly extending portions 19 and 20, there are preferably provided 15 the inclined metal straps 23, see Fig. 6. The portions 19 and 20 are provided with inwardly extending flanges 24 cut away at their upper ends to form a clearance for the angle irons 9.

The intermediate bed section 2 preferably includes two inverted U-shaped metal end members 25 having the intermediate angle irons 9 connected to one another by the cross-shaped reinforcing member 26, and the ends of the spring fabric 27 connected to the upwardly extending flanges 28 of the angle irons 9. The upwardly extending flanges 28 incline inwardly see particularly Fig. 6 so that the connecting loops of the spring fabric portion 27 may clear the edges of the flanges 24.

30 The cross-shaped reinforcing member 26 includes two angle irons 29 and 30 with their vertically extending flanges extending downwardly and their abutting faces at the middle 31 secured to one another as for instance by welding. These angle irons 29 and 30 are bent adjacent the middle 31 to engage one another substantially in alignment with the middle of the spring fabric 27 and are further bent adjacent their ends at 32 and 33 to form a downwardly extending loop see particularly Fig. 3.

40 The downwardly extending loop is formed so that the spring fabric 27 will be free to be depressed without interfering with any rigid bracing members.

45 The lower ends of the downwardly extending portions 34 of the end members 25 are provided with the casters 5 already referred to. The front longitudinally extending portion of the spring fabric 17 of the main bed section 1 preferably extends forwardly beyond the front faces of the downwardly extending portions 19 and 20, see Fig. 5. When operatively associated, the rear legs or downwardly extending portions 34 of the intermediate bed section 2 are positioned behind the crossbar 21 and substantially in alignment with the flanges 24, with the spring fabric 27 55 slideable under the spring fabric 17 and the angle irons 9 sliding in the clearance formed above the shoulders 35 of the flanges 24.

60 As an additional reinforcement for the spring fabric 17 of the main bed section 1, the front projecting edge is preferably provided with a flat flexible metal strap 36 connected by coil springs to the bed sections 37 of the crossbar portions 14 and 15.

65 The outer extension bed section 3 includes two end members 38 having laterally extending upper bars 39 and downwardly extending leg portions 40 at their front ends to the lower ends of which 70 are secured the casters 6 above referred to.

75 The front faces of the leg portions 40 are preferably connected to one another by the front decorative board member 41 and their upper ends by the angle iron 57; the rear ends of the laterally extending bars 39 are preferably provided with

the downwardly extending pins 7 already referred to, to ride upon the flanges 8 of the angle bars 9 of the intermediate bed section 2; and the laterally extending bars 39 are further connected to one another by and form the support for, the 5 spring fabric 42 of the extension bed section 3. The inner or rear ends of the laterally extending bars 39 are further connected to one another by the downwardly extending looped bracing member 43, see Fig. 3. The flanges 8 of the 10 angle irons 9 are preferably provided at their ends with upwardly extending limiting stops 52 and 53 for the pins 7 of the outer extension bed section 3. In operative association, the spring fabric 42 is adapted to slide under the spring 15 fabric 27.

Preferably the spring fabrics 27 and 42 of the extension bed members 2 and 3 are provided with cloth covers 44 and 45 respectively.

From the foregoing, it will thus appear that 20 in double bed formation the bars 18, 15 and 16 of the main bed section, the bars 9, 9 of the intermediate bed section and the bars 39, 38 and 57 of the outer bed section will form a rigid rectangular outer frame for the spring fabrics 17, 27 and 42 25 with sufficient clearance beneath the intervening spring fabrics 17, 27 and 42 to permit such spring fabrics freely to flex downwardly in use without encountering any objectionable obstacles.

The mattress or upholstered combination 30 forms an important part of the present invention. In the first place, two similarly dimensioned mattress members 46 and 47 are preferably hinged together as shown at 48. In length these mattress members correspond substantially to the distance between the arm portions 12, see Fig. 1, so that when folded upon one another, they will snugly cover the entire spring fabric 17 and lap over onto the front board 41, see Fig. 2, in love seat formation.

40 In double bed formation on the other hand when the bed sections 2 and 3 have been extended into the position shown in Fig. 4, the mattress portion 46 will lap over onto the rear portion of the spring fabric 27 of the intermediate bed section 2 and the mattress 47 will extend over the remaining part of the spring fabric 27 and lap over a goodly portion of the spring fabric 42 of the outer bed section 3. In addition to the mattress members 46 and 47, there are also provided two pillow members 49 and 50 which are preferably hinged at their adjacent edges at 51, see Fig. 2. These pillow members 49 and 50 in combined length extend the full length of the love seat, see Fig. 1, and in double bed formation 55 have a width which corresponds to the remaining uncovered portion of the spring fabric 42, that is corresponds in width to the width of the portion of the spring fabric 42, see Fig. 4, not covered by the mattress 47.

60 When describing the several bed sections, their length is described as the distance between the end members, which length will of course coincide with the width of the double bed section as distinguished from the length of such double bed 65 section from the rear bar 18 to the front board 41. In other words, the combined length of the individual bed sections although properly the length of the love seat will become the width of the bed in double bed formation produced 70 when the bed sections 2 and 3 are extended into the position shown in Fig. 5.

As will clearly appear from Fig. 4, while the length and width of the mattress member 47 are substantially the same as that of the mattress 75

member 46, it is considerably deeper than the mattress member 46, and the mattress members 49 and 50 are preferably at least as deep as the mattress member 47 if not a little deeper.

5 To reinforce the angle iron 21, the inner faces of the horizontally extending and vertically extending flanges thereof are connected by the angle iron reinforcement 55. Furthermore, some of the other corners not heretofore described in detail are also preferably reinforced, as an instance, the legs 54 are preferably connected to the angle iron 18 by the reinforcing straps 56; the laterally extending bars 39 are preferably connected to the horizontally extending flange of the angle iron 57 by the reinforcing straps 58; and the vertically extending flanges of the bars 39 are preferably connected to the legs 40 by the reinforcing straps 59.

It is of course obvious that the main section 1 may be only long enough to form a single seating space when the sections 1, 2 and 3 are telescoped into one another and cooperate with the sections 2 and 3 in extended position to form a full length single bed or couch without departing from 25 the general spirit of the invention.

It is obvious that various changes and modifications may be made to the details of construction without departing from the general spirit of the invention as set forth in the appended claims.

I claim:

1. The combination with a main bed section, of an intermediate bed section and an outer bed section slideable under said main bed section into love seat formation and slideable transversely of said bed sections into double bed formation, flat spring fabrics connected to said bed sections, parallel horizontally extending angle irons forming a part of said intermediate bed section having upwardly extending flanges to form supporting abutments for the spring fabric of said intermediate bed section, said main bed section having front legs including inwardly extending flanges cut away to form passageways for said angle irons, the upwardly extending flanges of said angle irons being bent toward one another in their upward direction to enable the upper ends of said vertically extending flanges to clear the inwardly extending flanges of said legs.

2. A pair of bed sections for a couch bed, one of said bed sections having end frames including horizontally extending flanges and downwardly extending legs having inwardly extending flanges extending above said horizontally extending flanges to form stops at the ends of said horizontally extending flanges, the other bed section having end frames including a pair of front legs, and a pair of short downwardly extending pins at the rear ends of the end frames slidably mounted on the horizontally extending flanges of said first bed section and cooperating with the stops thereof to limit the movement of said pins and therewith of said second bed section.

3. A bed section for a couch bed having end frames including horizontally extending angle irons, downwardly extending legs at the ends of said angle irons, the horizontally extending flanges of said angle irons extending toward one another and the vertically extending flanges extending upwardly from said horizontally extending flanges, two downwardly looped angle irons secured to the horizontally extending flanges of said end frames adjacent their ends with the middle portions of said downwardly looped angle irons bent toward one another and secured to

one another, and a flat spring fabric secured to the upper edges of the vertically extending flanges of said end frames.

4. The combination with a main bed section, of an intermediate bed section and an outer bed section slideable under said main bed section into love seat formation and slideable transversely of said bed sections into double bed formation, flat spring fabrics connected to said bed sections, parallel horizontally extending angle irons forming a part of said intermediate bed section having upwardly extending flanges to form supporting abutments for the spring fabric of said intermediate bed section, said main bed section having front legs including flanges extending inwardly toward one another, the upwardly extending flanges of said angle irons being bent toward one another in their upward direction to enable the portions of the flat spring fabric connected to the upper ends of said vertically extending flanges to clear the inwardly extending flanges of said legs.

5. The combination with a main bed section, of an extension bed section, said main bed section having end members, each comprising a horizontally extending angle iron and downwardly extending angle irons at the ends thereof forming a rear and a front leg, a longitudinally extending angle iron connecting the rear upper ends of said end members, and a second longitudinally extending angle iron connecting the lower ends of said front legs, one pair of webs of said front leg forming angle irons extending toward one another perpendicular to and away from the front ends of the other pair of webs of said front leg forming angle irons, one of the webs of said second longitudinally extending angle iron lying in a horizontal plane and connected to the lower ends of said other pair of webs, and the other web of said second longitudinally extending angle iron extending vertically upwardly from said first named web and connected at its ends to said first pair of webs, said extension bed section having end frames, each including a horizontally extending angle iron and downwardly extending angle irons at the ends thereof forming a rear and front leg, and a downwardly looped frame connecting the end frames of said extension bed section to one another, the rear legs of said extension bed section being slideable under said main bed section, the second longitudinally extending angle iron forming a limiting stop for the outward movement of said extension bed section, and a flat spring fabric connecting the angle irons of the end frames of each bed section, the longitudinally extending edges of the spring fabric of said extension bed section defining the longitudinal sides thereof and said looped frame bent inward and clearing the longitudinal sides of the extension bed section thus defined by its spring fabric to facilitate freely flexing the adjacent longitudinal edges of said spring fabrics in extended bed formation downwardly above said second longitudinally extending angle iron.

6. In a combined seat and bed, the combination with a main frame having rollerless front and rear legs and a stop bar having a vertically extending flange connecting the lower ends of said front legs of an intermediate extension frame and an outer extension frame both narrower than said main frame to facilitate effectively housing the same under said main frame in seat formation, front and rear legs for said intermediate extension frame, rollers for supporting the legs of said intermediate frame, the rear legs be-

- ing positioned to the rear of said stop bar, the rear end of said outer extension frame being slidably mounted on said intermediate extension frame, front legs on said outer extension frame, 5 rollers on said latter front legs positioned to travel in paths of travel parallel to but inwardly of the paths of travel of the front legs of said intermediate frame, said stop bar not only serving as a limiting stop for the rear legs of said 10 intermediate frame in bed formation but also as limiting stops for the rollers of the front legs of both said intermediate and outer frames in seat formation.
7. A pair of bed sections for a couch bed, one 15 of said bed sections having angle iron end bars with the horizontally extending webs extending toward one another from the lower ends of the vertically extending webs of said end bars, a spring fabric connected to the upper ends of the 20 vertically extending webs and spaced from said horizontally extending webs, and legs at the ends of said end bars for independently supporting said bed section, the other bed section having end frames including angle iron end bars with 25 the horizontally extending webs extending away from one another from the upper ends of the vertically extending webs of said end bars, a spring fabric connected to said latter angle iron end bars adjacent the upper ends of their vertically 30 extending webs, abutments extending downwardly from the rear ends of said latter horizontally extending webs, and legs disposed inwardly of and connected to the inner faces of the front ends of the vertically extending webs 35 of said other bed section to clear the legs of said first mentioned bed section in telescoped position with the abutments slidably mounted on the horizontally extending webs of said first pair of end bars and with the horizontally extending webs

of said other bed section slidably mounted between the horizontally extending webs and the spring fabric of said first mentioned bed section.

8. A bed section for a couch bed having end frames including angle irons with one of their webs extending inwardly toward one another from the lower edges of their other and vertically extending webs, downwardly extending angle irons forming legs at the ends of said end frame angle irons with their outer webs connect- 5 ed to the outer faces of said vertically extending webs, a downwardly looped frame including two angle irons secured to one another at adjacent intermediate portions of their vertically extending webs with their other webs extending away 10 from one another and their ends connected to the inwardly extending webs of said end frame angle irons, and a flat spring fabric secured at its ends to the upper edges of the vertically extending webs of end frame angle iron, the inwardly 15 extending webs of said leg forming angle irons cut away at their upper ends to clear the passage formed between said spring fabric and the inwardly extending webs of said end frames.

9. The combination with a main bed section, 25 of an extension bed section slidable under said main bed section into love seat formation and slidable transversely of said bed sections into double bed formation, flat spring fabrics connected to said bed sections, parallel horizontally 30 extending angle irons forming a part of said intermediate bed section having upwardly extending flanges to form supporting abutments for the flat spring fabric of said intermediate bed section, said main bed section having front legs in- 35 cluding flanges extending inwardly toward one another, said flanges having a part cut away to form passages for said angle irons.

JOSEPH MARTIN.
